UNITED STATES PATENT OFFICE.

DAVID H. GILLESPIE, OF LOCKLAND, OHIO.

BRIDLE-BIT.

SPECIFICATION forming part of Letters Patent No. 498,644, dated May 30, 1893.

Application filed October 31, 1892. Serial No. 450,431. (No model.)

To all whom it may concern:

Be it known that I, DAVID H. GILLESPIE, a citizen of the United States, residing at Lockland, in the county of Hamilton and State of Ohio, have invented a certain new and useful Improvement in Bridle-Bits, of which the following is a specification.

The object of my invention is to provide a bridle bit by which a hard mouthed or vicious animal may be controlled and which will not cause discomfort in ordinary use. The invention consists in the construction and arrangement of parts hereinafter described and claimed.

15 In the drawings: Figure 1 is a front view of a bridle bit embodying my invention, the rings being shown in a vertical plane. Fig. 2 is a like view showing the rings in a horizontal plane.

20 A, A are the rein rings. B is a central ring.

C C are links connecting the rings with the central ring there being a pair of links on each side.

25 D D are loops taking over the central ring and between the pairs of links C. I prefer to make all the connections loosely so that each part will be capable of movement relatively to the other parts. Duplicating the 30 links makes it practically impossible for the animal to hold the bits firmly between the teeth against a sawing action of the reins, and maintaining a space between the ends of two links composing a pair by one or more loops

D or equivalent means makes it impossible 35 for the animal to hold the bit fast.

It will be noticed that in the construction described and shown the links, when there is a strain upon the reins, normally assume a position parallel with each other in a plane at 40 right angles to the mouth of the animal and it is practically impossible for the animal to grasp them in such a way as to hold them fast as he might grasp and hold double barred bits in which the bars are parallel, when under strain, in a plane coincident with the mouth of the animal.

It is obvious that the loops D may be omitted and that the bit will still be effective though for a hard-mouthed animal I prefer to 50 use the loops.

I claim--

1. The combination in a bridle bit of the rein rings A, the central ring B, and pairs of links C C each pair connecting one of the rein 55 rings A with the central ring B, substantially as and for the purpose specified.

2. The combination in a bridle bit of the rein rings, a central ring, pairs of links connecting the rein rings and the central ring 60 and one or more loops taking around the central ring between the connecting links, substantially and for the purpose specified.

DAVID H. GILLESPIE.
